A. L. JUST.

DUST CAP.

APPLICATION FILED DEC. 26, 1919.

Patented Apr. 20, 1920.

UNITED STATES PATENT OFFICE.

ALVAH L. JUST, OF SYRACUSE, NEW YORK.

DUST-CAP.

1,237,606.

Specification of Letters Patent. Patented Apr. 20, 1920.

Application filed December 26, 1919. Serial No. 347,254.

To all whom it may concern:

Be it known that I, ALVAH L. JUST, a citizen of the United States, residing at Syracuse, in the county of Onondaga and State 5 of New York, have invented certain new and useful Improvements in Dust-Caps, of which the following is a specification.

This invention relates to improvements in dust caps, and has for its object to provide 10 novel and simple means for protecting the valve stems of pneumatic tires and the like. A particular object is to provide a dust cap which may be readily and quickly attached to and detached from the threaded valve 15 stem without requiring the cap to be screwed and unscrewed in a tedious manner during said operations. And a further object is to provide novel and simple means for locking the dust cap in the closed position, as well 20 as for rendering the joint between the dust cap, the valve stem and the felly of the wheel waterproof.

I attain these objects by the means set forth in the detailed description which follows and as illustrated by the accompanying drawing, in which—

Figure 1 is a fragmentary section of a wheel and its pneumatic tire to which my device is applied. Fig. 2 is an inverted central longitudinal section taken on line 2 of Fig. 1. Fig. 3 is a similar view of the dust cap alone, the same being partially in section. Fig. 4 is a central vertical cross-section taken through the sections of the split 30 nut, on line 4 of Fig. 2. Fig. 5 is a horizontal section taken on line 5—5 of Fig. 2. Fig. 6 is a similar section taken on line 6—6 of Fig. 3. Fig. 7 is a top view of one of the sections of the split nut. Fig. 8 is a broken 35 elevation of the dust cap; showing the split nut spread apart to slip loosely over the threaded valve stem. Fig. 9 is a bottom view of the compressible washer. Fig. 10 is respectively a top view and central section 40 of the metal washer which locks the dust cap in the closed position. Fig. 11 is a side elevation of the split nut; showing one of the spreading springs.

In the drawing, 2 is the felly of a wheel; 50 3 is the usual metal rim; 4 is the outer shoe of the tire, and 5 is the inner or pneumatic tube. 6 is the threaded valve stem which passes loosely through the several parts of the wheel and tire, and is held in place on 55 the tube 5 by a nut 6'. The valve stems 6 are usually threaded substantially their full

length and their outer ends comprise reduced nipples 6^a, to which an air pump may be connected in a well-known manner for inflating the tube 5. The stem 6 in passing 60 loosely through the rim and felly projects some distance beyond the felly, and this portion of the stem is usually protected by a hollow tubular dust cap having one open end which is usually internally threaded, 65 and to apply and remove these old dust caps, they are generally screwed the full length of the projecting ends of the valve stems. These operations usually require many turns of the caps in order to bring 70 them to a stop against the felly of the wheel so as to properly exclude the dust and water. These operations not only consume considerable time but, as the valve stems are invariably positioned between adjacent closely 75 disposed spokes of the wheel, the spokes greatly interfere with the convenient and rapid turning of the cap. In the present invention the threads are omitted from the dust cap 7 and in lieu thereof the open end 80 7 is enlarged and its opposite inner sides are fitted with radial pins 7^a and 7^b which align axially and which engage similar half sections 9' and 9^a of a split nut 9, which 85 slidably telescopes the expanded end of the cap 7. The sections 9' and 9^a of the nut are provided with similar L-shaped slots 9^b, which receive the pins 7^a and 7^b of the cap. At least one of the pins 7 is applied to the cap 90 after the nut has been inserted, and thereafter the nut is held from full release from the caps by said pins, as best seen in Fig. 8. By the provision of the L-shaped slots 9^b, the nut may be extended the distance allowed by the vertical portions of said slots 95 and then spread apart for freeing the threads 9^c of the sections from the threads of the valve stem, so that the cap may be removed and replaced readily and quickly without requiring any screwing, as heretofore. In order to facilitate the spreading of the sections of the nut I employ similar 100 springs 10 which are preferably folded upon themselves and their outwardly bent ends inserted in sockets 10' which are formed in the lower inner faces of the sections, as shown. In order to permit the sections of the split nut to spread apart, (the nut when assembled being circular), the corresponding top corners of the sections 9' and 9^a are 105 cut away at 9^d, as best seen in Figs. 4, 8 and 11. The spreading of the nut is limited by

lugs 13 and sockets 13'. When the cap is applied to the valve stem 6 the springs 10 hold the sections spread apart as shown in Fig. 8, and when the outer ends of the nut 5 sections engage the washer which rests upon the felly, a slight pressure on the cap forces the sections of the nut back into the expanded portion 7' of the cap and compresses the springs 10, as shown in Fig. 11. After 10 the cap has been placed in position on the stem, as described, the cap is given a slight twist or turn for moving the pins 7^a—7^b into the horizontal arms of the L-shaped slots, where they are allowed to remain until the 15 cap is removed. 11 represents a washer, preferably of some compressible material, which lies against the felly 2. Upon this washer is disposed a circular piece of tin or copper 12, having a central opening 20 which substantially conforms to the cross-sectional area of the valve stem, so that the washer may be held from rotation. At the time the hole is punched in the metal washer 12, lugs or clips 12' are struck out, and when 25 the two washers are placed together, these two clips are folded downwardly and outwardly and clenched for holding the two pieces together (see Fig. 9). The top surface of the washer 12 is provided with a 30 number of radial ribs 12^a which engage similar shallow V-shaped notches 7^c formed in the bottom edge of the cap. The object of these ribs and notches is to lock the cap in the closed position and prevent it from 35 jarring loose by the vibration of the wheel while the vehicle is in motion.

The operation of my dust cap is as follows: When a new tire is placed on the wheel and the valve stem 6 is inserted through the 40 felly 2, the operator slips the connected washers 11—12 over the stem until they bear against the face of the felly. He next takes the dust cap 7 and pulls out the nut 9 as far as it may move on the pins 7^a and 7^b. 45 As soon as the nut is withdrawn the springs 10 spread the sections, as shown in Fig. 8. The cap with the protruding nut is then slipped over the stem 6, and the free end of the nut is pressed against the washer 12 until the nut is forced entirely back into the 50 cap, as shown in Fig. 2. This operation causes the pins of the cap to move downwardly the length of the vertical arms of the slots 9^b and also forces the threads of the 55 nut into mesh with the threads of the stem 6. The final operation consists of giving

the cap a partial turn for moving the pins into the horizontal arms of the L-shaped slots, and at the same time effecting the locking of the cap to the washer 12 by the 60 notches 7^c engaging one or more of the ribs 12^a, as described.

Having thus described my invention, what I claim as new and desire to secure by Letters Patent, is—

65

1. The combination with a hollow dust cap having radial pins near its open end, of a split nut telescopmg the cap and internally threaded for engaging the threads of a valve stem, the sections of said nut provided with 70 L-shaped slots to receive said pins, and having sockets in their radial faces, each of said sections having circumferential tongues and slots for limiting the spreading of the sections, and a plurality of springs engaging 75 said sockets adapted to spread said sections for freeing said nut from the threads of the valve stem.

2. In a dust cap for valve stems, the combination with a hollow cylindrical cap having one open end provided with a plurality of notches, and having oppositely facing radial pins, of a split nut slidably telescoping the open end of said cap, each section of said nut having an L-shaped slot to receive the 85 corresponding radial pin, the ends of said slots being closed for preventing the detachment of said parts, the sections of said nut each having corresponding sockets and having threads to engage the threads of a valve 90 stem, springs engaging said sockets adapted to spread the sections of the nut when the latter is partially withdrawn from the cap, and means engaging the notches in said cap for locking the cap in the closed position.

95

3. The combination with a dust cap having oppositely facing radial pins near its open end, and a plurality of notches in said end, and a washer having radial ribs adapted to engage said notches, of a split nut 100 slidably telescoping the open end of the cap, said nut having threads to engage the threads of a valve stem, and having L-shaped slots to receive said pins, the meeting edges of the sections of said nut provided with alining sockets, springs engaging the corresponding sockets and adapted to spread said sections for freeing the nut from the valve stem, and means for limiting the spreading of said sections.
